Primary Examiner — Derrick E Holland*(74) Attorney, Agent, or Firm* — Finnegan, Henderson, Farabow, Garrett & Dunner, LLP(57) **CLAIM**

The ornamental design for an electric motor and generator, as shown and described.

DESCRIPTION

FIG. 1 is a front, top, left perspective view of an electric motor and generator, showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines of even length shown in the drawings illustrate portions of the electric motor and generator that form no part of the claimed design.
